Primary Examiner—Cathy Anne MacCormac
Attorney, Agent, or Firm—Wood, Herron & Evans[57] **CLAIM**

The ornamental design for the veterinary isolation cage, as shown and described.

DESCRIPTION

FIG. 1 is a perspective view of a veterinary isolation cage showing our new design;

FIG. 2 is a front elevational view thereof;

FIG. 3 is a right side elevational view thereof;

FIG. 4 is a rear elevational view thereof;

FIG. 5 is a top plan view of FIG. 7;

FIG. 6 is a bottom view of FIG. 7;

FIG. 7 is a perspective view of a second embodiment of FIG. 1;

FIG. 8 is a front elevational view of FIG. 7;

FIG. 9 is a left side elevational view of FIG. 7;

FIG. 10 is a right side elevational view of FIG. 5; and,

FIG. 11 is a rear elevational view of FIG. 5.

The top plan and bottom views of the first embodiment of FIGS. 1-4 would look the same as FIGS. 5 and 6 except there would be no bracket around the outside of the legs. The broken lines are for purposes of illustration only and form no part of the claimed design.
